APPARATUS FOR ELECTROPLATING OF
BEARING SHELLSCarroll F. Matthews, Indianapolis, Ind., assignor
to General Motors Corporation, Detroit, Mich.,
a corporation of Delaware

Application October 27, 1942, Serial No. 463,484

10 Claims. (Cl. 204—272)

1

This invention relates to the art of plating by electrolysis and has particular reference to plating a coating of silver on the inside of the bearing shells used to support the crankshafts of airplane engines.

The present invention is an improvement over the application of George A. Zink and Carroll F. Matthews Serial Number 350,046, filed August 2, 1940 for Bearing and method of making same.

In the prior application mentioned, apparatus is disclosed to plate but a single bearing, while in the instant application the apparatus will plate two or more bearings simultaneously in the same bath. For purposes of illustration, three bearings are shown in the apparatus disclosed on the drawings.

The manner of cleaning the bearing shell and preparing it with a copper coating preparatory to receiving the silver coating is described and claimed in the copending application mentioned in the foregoing.

The improvement in the instant application relates to a fixture immersed in a container having the electrolytic bath. The fixture comprises an upright propeller tube at the bottom of which there is applied a marine impeller driven by an electric motor suspended outside of and over the container. The bottom of the tube has connected thereto a plurality of pipes (three in the present instance) which radiate therefrom in a single plane. The pipes are turned upwardly at their ends, and at the end of the upturned part there is mounted the apparatus for plating the bearing shells with silver.

The impeller at the bottom of the tube forces the electrolytic solution through the pipes and through a plug having spiral slots at its edge. The liquid is forced through the spiral slots and into the cathode containing the bearing shells. The spiral slots will give a slight spinning motion to the liquid and cause it to spin or whirl around and continue to circulate as it is moved upwardly past the bearing shell by the motion given to the liquid by the impeller.

The anode comprises a hollow perforated stationary hard rubber tube mounted inside the cathode and having a fabric (muslin, glass, or the like) wound thereabout, the fabric, however, being pervious to the liquid and enabling the passage of the silver ions to the cathode. The hollow perforated anode tube is secured to a metal anode plug, and to a central bore in the plug a smaller metal tube is secured. The anode (comprising the rubber tube, the metal tube and the plug) is removable and the space between the

2

two tubes is filled with suitable silver balls or chunks of silver to replenish the silver deposited from the liquid by the electrolytic action.

On the drawings:

Figure 1 is a perspective view of the electrolytic bath with the apparatus mounted therein, a part of the container being broken away better to illustrate the apparatus.

Figure 2 is an enlarged detailed sectional view through one of the elements of the apparatus and showing the propeller tube partly broken away to illustrate the application of the impeller.

Figure 3 is a section on the line 3—3 of Figure 2.

On the drawings, the numeral 2 indicates the tub or bath in which the electrolyte is contained. This bath is positioned below a frame (not shown) on which there is mounted an electric motor (not shown) which drives a shaft 4.

At the end of the shaft there is connected a marine impeller 6 which is mounted at the lower part 10 of an upright propeller tube 12, the top of which is below the level of the electrolytic solution. The tube 12 has suitably connected at its lower end the radiating tubes 14, 16, and 18, the outer ends of which are upturned as indicated at 20, 22, and 24. Where the upturned ends 20, 22, and 24 join onto the main tubes the joint is flattened at 26 to form a baffle, the purpose of which is to cause the liquid to move more evenly or smoothly upwardly in the ends 20, 22, and 24. At the upper part of each upturned tubular end 20, 22, and 24, locating rings or plates 28, 30, and 32 are secured.

The propeller tube 12 and the pipes 14, 16 and 18 are welded as at 31 to a frame 33 formed of four strips of metal placed at right angles to each other to form a square with the ends of the strips projecting beyond the square, as shown.

This frame is not secured to the bottom of the container but rests freely thereon to enable the ready removal of the frame and the apparatus.

At the top of each upturned part 20, 22, or 24, an electroplating assembly is mounted, and as they are all similar, the description of one will suffice for the description of all.

A spray shell 34 is secured by means of the bolts 36 to the ring 28, and inside the spray shell a rubber spiral spray plug 38 is secured. This plug is provided at its periphery with the spiral passages 40, through which the electrolyte is forced by the impeller 6 located at the bottom of the propeller tube 12. The spray shell 34 is beveled at its upper end at 42, the purpose of the bevel being to receive a corresponding beveled

part of a mask fixture MF shown in detail in Figure 2. A cone 45 at the bottom of the plug 38 directs the flow of solution into the spirals 40 and reduces resistance to free flow of solution.

The spiral spray plug 40 has a recess 43 at its upper part and in the recess there is mounted the metallic contact or spray plug 44 threadedly connected as at 46 to a contact rod 48 covered with a rubber tubing 50. The contact rod 48 extends upwardly out of the solution as best indicated in Figure 1.

Over the contact 44 there is removably positioned a metal anode plug 52, the lower part of which is in the recess 43 in the spiral spray plug 38 and the upper part 53 of which projects outwardly over the top surface of the plug. The top outwardly projecting part 53 is reduced as indicated at 54, and over this reduced part there is received the hollow perforated hard rubber anode tube 56. The tube 56 is secured to the anode plug 52 by means of the pins 58.

The spiral spray 38, the spray plug 44 and the anode plug 52 have a bore through which there passes a cold rolled steel rod 60, the upper end 61 of which projects beyond the top of the rubber anode 56.

A steel tube 62 surrounds the rod 60 and extends downwardly into and is secured in the bore of the anode plug 52 and its bottom rests on the spray plug 44 immediately adjacent the bore in the plug. The top of the tubing 62 also extends beyond the top of the anode 56.

The anode tube 56 is purposely made hollow in order that it may receive a plurality of balls or chunks of silver 63 to replenish the silver which is removed from the bath in the electrolytic process. Preferably, the anode tube 56 has wound therearound a suitable fabric 65, preferably muslin, which is not attacked by the solution but which is pervious to the electrolyte.

The anode comprising the perforated rubber tube 56, the fabric 65 wound thereabout, the metal conducting tube 62, and the anode plug 52 are secured together and removable from the apparatus as a unit. The reason for the removability is to enable the anode to be cleaned, to replace the fabric 65, changing the anode size for different size bearings, etc.

The mask fixture MF which contains the bearing shells to be silver plated, and which comprises the cathode of the apparatus, is shown in detail in Figure 2. The bottom of the mask fixture is formed of a ring of metal 64 over which there is positioned a ring-shaped molded rubber mask 66. The mask 66 has an interior shoulder 68 on which there is adapted to seat two of the bearing shells 70 which are to be electroplated. This mask 66 is also provided with a reduced upwardly-projecting part 72, the purpose of which will be later described.

At one side of the mask 66 there is a bore 74 through which there passes a wire or rod 76 which forms an electric contact. The inner end 78 of this rod is in contact with the outer surface of the bearing shell 70 while the outer end of the rod 76 extends upwardly out of the solution and is adapted to contact with one of the leads (not shown) through which the current passes back to the source. The bearing shells 70 are in contact with each other at their parting lines 81.

At the top of the bearing shells 70 a molded rubber ring 82 is positioned, and on top of the ring 82 a second pair of bearing shells 70a, similar to the shells 70, are positioned. An outer steel ring 84 is positioned across the two shells

70 and 70a and an inwardly projecting rib 86 fits between the two bearing shells 70 and 70a, the ring 82 being of slightly less diameter than the outer diameter of the shells in order to accommodate the rib 86. The purpose of the ring 84 is to conduct the current between the shells and to hold the shells in a more rigid stack.

At the upper end of the bearing shell 70a a second molded rubber mask or ring 88 is mounted. This mask 88 has a shoulder 90 to receive the upper end of the bearing shells 70a. The mask 88 likewise has a bore 92 to receive a wire or rod 94 forming an electrical conductor. The end 96 of the rod 94 is in contact with the upper bearing shells 70a while the outer end extends upwardly out of the liquid and is connected to one of the leads (not shown) through which the current passes back to the source.

Both contact rods 76 and 94 are covered exteriorly with a rubber tubing indicated at 98, and both are retained on the masking fixture MF by the retainer 99.

Over the top of the mask 88 a metal ring 100 is mounted. The ring 100 is provided with suitable lateral openings and the ring 64 at the bottom is provided with similar mating openings. Preferably there are two openings to each ring located 180° apart. Through the openings there pass the retaining rods 102, each having a pin 104 therethrough at its upper end, and this pin strikes against the upper surface of the ring 100 while a nut 106 is screwed onto the lower end of the rods and tightly holds the assembly together.

In order to prevent the silver in the electrolyte from being deposited on the outside of the bearing shell, both bearing shells 70 and 70a are covered by an outer mask 108 composed of suitable nonconducting material such as rubber. This mask 108 fits at one end over the projecting part 72 of the lower rubber mask 66 and at its upper end over the projecting part 110 of the upper rubber mask 88.

The assembly MF as shown in Figure 2 is positioned around the anode 56 and when in position the beveled or chamfered part 112 of the lower ring 64 fits over the beveled or chamfered part 42 on the spray shell 34 tightly to hold the assembly MF on the spray shell.

The current coming from any suitable source will enter through the lead rod 48, pass to the spray plug 44, the anode plug 52, the rod 62, and then into the electrolytic solution. It will then pass through the solution across to the walls of the shells 70 and 70a and from the shells through the conducting rods 76 and 94 out of the solution and back to the source. The current in passing from the anode to the cathode across the electrolyte will cause the silver in the solution to deposit on the interior of the shells 70 and 70a.

During the operation of the electrolytic process, the impeller 6 at the bottom of the propeller tube 12 will force the solution through the tubes 14, 16, and 18 and out through the spiral passages 40 to cause it to pass slowly upward in a slight swirling way past the inner faces of the bearing shells 70 and 70a and toward the top of the anode tube 56. The solution will spill over the top of the anode and into the bath in the container 2 and be recirculated by the impeller. This process will continue until the desired amount of silver has been deposited on the interior of the shells 70 and 70a.

As fast as the silver is deposited from the solution by the electrolytic process, the solution will dissolve additional replacement silver from the

silver balls or chunks 63 inside the anode. In this way the amount of silver in solution is kept substantially constant.

Referring to Figures 1 and 2, it will be noted that a baffle B has been secured inside the propeller tube 12. The purpose of this baffle is to prevent the swirling of the liquid in the tube and to enable it to pass down in a smooth and quiet way to the impeller 6. The baffle B is not sufficiently wide to prevent the impeller 6 and its shaft 4 from being withdrawn from the tube 12.

On the drawings the invention is disclosed as applied to three units or masking fixtures, each fixture having two sets (70, 70 and 70a, 70a) of bearing shells. The invention is capable of adaptation to two, four or more masking fixtures, each of which may use one, two or more sets of bearing shells, the application of the invention being limited only by practical or mechanical limitations. For example, the propeller tube may be placed at the center of four pipes which radiate from the propeller tube 90° apart and at whose upturned ends masking fixtures and anodes are mounted.

If desired, the rubber spiral spray plug 38 may be eliminated and the electrolyte caused to flow upwardly between the anode and the cathode without imparting thereto any swirling motion. In case the spiral spray plug 38 is not used, the contact plug 44 can be supported by the rod 48 alone or by insulated arms positioned under the plug 44 and having their ends secured to the inside wall of the shell 34.

When the desired amount of silver has been plated on the bearing shells, the cathode or masking fixture MF is removed from the bath by lifting it upwardly over the anode and out of the solution. The rods 102 are now released to enable the masking fixture to be taken apart, the plated shells are removed, and unplated shells are placed in the fixture. The masking fixture can now be reapplied and the plating process recommenced to plate the new shells.

When it is desired to clean or change the anode, the unit comprising the perforated rubber tube 56, the metal tube 62 and the plug 52, is removed. The anode can now be taken apart by removing the covering 65 of fabric and then removing the pins 58 to enable the rubber tube to be separated.

I claim:

1. In an apparatus for electroplating the bearing shells of bearings of crankshafts used on internal combustion engines, a container having an electrolytic solution therein, an assembly fixture comprising a tube having a plurality of pipes connected thereto and extending therefrom, said assembly fixture being immersed in the electrolytic solution, an anode mounted on the end of each pipe, a cathode mounted on the end of each pipe and surrounding the anode in spaced relation, said cathodes comprising bearing shells, means to circulate the electrolytic solution from the tube into the pipes and into the space between the anode and cathode, and means to conduct an electric current through the anodes and cathodes and across the electrolyte to cause a deposit of metal from the electrolyte on the bearing surface of the bearing shells.

2. The invention of claim 1, the end of each pipe having a plug mounted therein, and a spiral passage in the plugs to give the liquid a slightly swirling motion as it passes upwardly in the space between the anodes and cathodes.

3. In an apparatus for electroplating the bearing shells of bearings of crankshafts used on in-

ternal combustion engines, a container having an electrolytic solution therein, an assembly fixture comprising a tube having a plurality of pipes connected thereto and extending therefrom, said assembly fixture being immersed in the electrolytic solution, an anode mounted on the end of each pipe, a cathode mounted on the end of each pipe and surrounding the anode in spaced relation, said cathodes comprising a plurality of pairs of bearing shells, means to space each pair of shells from the adjacent pair of shells, an impeller in the tube to circulate the electrolytic solution from the tube into the pipes and into the space between the anode and cathode, and means to conduct an electric current through the anodes and cathodes and across the electrolyte to cause a deposit of metal from the electrolyte on the bearing surface of the bearing shells.

4. In an apparatus for electroplating the bearing shells of bearings of crankshafts used on internal combustion engines, a container having an electrolytic solution therein, an assembly fixture comprising a tube having a plurality of pipes connected thereto and extending therefrom, said assembly fixture being immersed in the electrolytic solution, an anode mounted on the end of each pipe, a cathode mounted on the end of each pipe and surrounding the anode in spaced relation, said cathodes comprising bearing shells and being removably positioned on the pipe ends to enable the removal and replacement of the bearing shells, means to circulate the electrolytic solution from the tube into the pipes and into the space between the anode and cathode, and means to conduct an electric current through the anode and cathode and across the electrolyte to cause a deposit of metal from the electrolyte on the bearing surface of the bearing shells.

5. In an apparatus for electroplating the bearing shells of bearings of crankshafts used on internal combustion engines, a container having an electrolytic solution therein, an assembly fixture comprising a tube having a plurality of pipes connected thereto and extending therefrom, said assembly fixture being immersed in the electrolytic solution, an anode mounted on the end of each pipe, a cathode mounted on the end of each pipe and surrounding the anode in spaced relation, said cathode comprising bearing shells, means embodied in the cathode to mask the outer surface and ends of the shells to prevent the plating of the outer surface and ends, means to circulate the electrolytic solution from the tube into the pipes and into the space between the anode and cathode, and means to conduct an electric current through the anode and cathode and across the electrolyte to cause a deposit of metal from the electrolyte on the bearing surface of the bearing shells.

6. In a cathode apparatus for electroplating the bearing shells of bearings of crankshafts used on internal combustion engines, a mask, a pair of bearing half shells positioned on the end of the mask, a second pair of bearing half shells positioned adjacent the first shells, means spacing the second pair from the first pair of shells, a second mask positioned on the end of the second pair of shells, a cover of nonconducting material over the outside of the shells, means to hold the masks and shells in assembled relation, and current conducting leads mounted in the masks and connected with each pair of bearing shells.

7. In a cathode apparatus for electroplating the bearing shells of bearings of crankshafts used in-

on internal combustion engines, a first mask, a second mask, a plurality of superimposed aligned pairs of bearing half shells positioned between the masks and spacing them from each other, a cover of nonconducting material over the outside of the shells, means removably to hold the masks and shells in assembled relation, and current conducting leads mounted in the masks and connected with the end pairs of bearing shells.

8. In an apparatus for electroplating the bearing shells of bearings of crankshafts used on internal combustion engines, a container having an electrolytic solution therein, an assembly fixture comprising a tube and a pipe connected thereto and extending away therefrom, said assembly fixture being immersed in the electrolytic solution, an anode mounted on the end of the pipe, a cathode mounted on the end of the pipe and surrounding the anode in spaced relation, said cathode comprising bearing shells, means in the tube to circulate the electrolytic solution from the tube into the pipe and into the space between the anode and cathode, and means to conduct an electric current through the anode and cathode and across the electrolyte to cause a deposit of

25

metal from the electrolyte on the bearing surface of the bearing shells.

9. The invention of claim 8, said means in the tube to circulate the electrolytic solution comprising an impeller positioned inside the tube near the bottom thereof.

10. In an apparatus for electroplating the bearing shells of bearings of crankshafts used on internal combustion engines, a container having an electrolytic solution therein, an assembly fixture comprising a tube and a pipe connected thereto and extending away therefrom, said assembly fixture being immersed in the electrolytic solution, a plug secured to the end of the pipe, an anode mounted on the plug, a cathode mounted on the plug and surrounding the anode in spaced relation, said cathode comprising bearing shells, means in the tube to circulate the electrolytic solution from the tube into the pipe and into the space between the anode and cathode, and means to conduct an electric current through the anode and cathode and across the electrolyte to cause a deposit of metal from the electrolyte on the bearing surface of the bearing shells.

CARROLL F. MATTHEWS.
